ATOMIZING DEVICE

Arthur John Adams, Westbury, England

Application October 7, 1932, Serial No. 636,763

8 Claims. (Cl. 299—140)

This invention relates to atomizing or disintegrating devices adapted for spraying liquids or fluids. The principal object of the invention is to provide an improved and efficient atomizing or spraying nozzle which, while particularly adapted for use in humidifying or air-conditioning apparatus, is capable of use generally wherever it is desired to provide a fluid spray or mist. Many uses to which the device may be applied will occur to persons familiar with the art of atomizing fluids, and need not be specifically mentioned here.

Another object of the invention is to provide a device of this nature which comprises few relatively simple parts that may be readily removed or disassembled when desired.

A further object of the invention is to provide an atomizing device which incorporates certain features of construction that mutually contribute toward a generally improved device. By virtue of these structural features, complete and efficient atomization or disintegration of the fluid is obtained.

The invention in a preferred form is illustrated on the accompanying drawing to which reference may be had in connection with the following description.

In the drawing:

Fig. 1 is a side elevational view of the device; Fig. 2 is a face view looking at the device from the left side thereof as illustrated in Fig. 1; Fig. 3 is a sectional elevation of the device; and Figs. 4 to 7 are sectional views taken respectively along the arrow head lines of Fig. 3 bearing corresponding numerals.

Referring to the several views of the drawing, the device in the preferred form comprises essentially a tubular barrel 1 within which is disposed a plug 2. The barrel is generally cylindrical in form having the central bore opening 3 extending longitudinally therethrough within which plug 2 is snugly seated. The barrel is provided with a threaded opening 4 which receives the threaded end of an air inlet pipe 5. The other end of this pipe is enlarged and threaded as at 6. The central bore opening 7 of this pipe has one end flared as at 8 and adapted to snugly receive the tapered nozzle head 9 of a tubular coupling member 10, thus forming an air-tight joint. A cap 11 is threadedly secured to the enlarged head 6 of pipe 5 and serves to firmly attach coupling member 10 to the pipe. To this end, the annular shoulder 12 is provided on head 9 and this shoulder is engaged by the flange of cap 11 surrounding the opening 13 of the cap through

which coupling member 10 extends. Member 10 may be connected to a pipe or hose leading to a suitable source of compressed air. By virtue of the construction of the device, air at relatively low pressure may be used and this is an important advantage.

One end of barrel 1 is threaded as at 14 and receives a cap 15 which serves to secure the tubular coupling member 16 to the barrel. The flanged head 17 of member 16 is engaged by the flange 18 of cap 15. The internal surface of the end of bore opening 3 is flared at 19 and it is adapted to snugly receive the flared end 20 of plug 2 to form a tight joint and to limit the longitudinal movement of the plug relative to the barrel. A suitable washer 21 is interposed between the end of plug 2 and the flanged end of coupling member 16. In this manner, the coupling member is secured to the barrel, plug 2 is held in the bore opening, and a tight joint is effected. Member 16 may be connected to a pipe or hose leading to a suitable source of liquid (not shown) which it is desired to atomize. Although the specific structures above described for securing coupling members 10 and 16 to barrel 3 are preferred, it is to be understood that any other suitable means for serving this purpose may be utilized.

It is intended that plug 2 be removably associated with barrel 1 and readily removable therefrom by merely uncoupling member 16 and sliding the plug from the barrel. In order to insure that plug 2 shall be properly positioned within the barrel at all times and rotary movement of the plug prevented, a transverse pin 22 is carried by the plug and has an extending end 23 adapted to ride in a longitudinal groove 24 formed in bore opening 3, as shown more clearly in Fig. 4. This groove is cut in the internal cylindrical surface of the bore opening and extends from the end thereof longitudinally of the bore opening for a suitable length. Plug 2 has a cylindrical portion 25 which is of such diameter that it fits snugly within the cylindrical space inside barrel 1. The plug is diminished in diameter at 26 at a point immediately adjacent the mouth of pipe 5. This provides an annular space 27 between the plug and the barrel through which air from pipe 5 may circulate. Portion 28 of plug 2 is flattened and preferably formed as a triangular prism with flat faces 29 and rounded apexes 30 (see Fig. 5). The rounded apexes conform with the internal cylindrical surface of barrel 1 and snugly engage the same. It will thus be noted that plug 2 snugly engages the internal surface of the barrel 55

at spaced points, viz., at the cylindrical portion 25 of the plug and at the rounded apexes of the prismatic portion of the plug. Although it is preferred that the prismatic portion of the plug be triangular, any other suitable prismatic form may be given to the portion. By virtue of this structure, three air passages 31 are provided between the faces 29 and the internal surface of the barrel. The air circulating in the annular chamber 27 may flow along these passages as will be apparent. The tight fit between portion 25 of the plug and barrel 3 prevents the flow of air in the other direction.

A cap 32 fits snugly over the other end of plug body 2 and is secured thereto in any desired fashion so as to in effect constitute a part of the plug body. Plug 2 is provided with a central longitudinal bore opening or passage 33 which aligns with the bore opening of coupling member 16 and is adapted to receive the liquid therefrom which it is desired to atomize. The bore opening 33 terminates short of the end of plug 2 and communicates with a pair of spaced transversely extending passages 34 which lead to the annular space 35 (see Fig. 6). This annular space constitutes a mixing chamber, wherein the liquid and air mix. It is very important to note that the mouths of the liquid passages 34 are aligned axially with two of the triangular faces 29 and the adjacent air passages 31 so that the liquid emitted by passages 34 is directly in the path of the air streams through these air passages. The reason for this construction will be more clearly understood as the description proceeds.

A pair of spaced grooves 36 (see Figs. 6 and 7), which are in axial alignment with two of the apexes 30, are cut in the outer cylindrical surface of the plug body and extend from a point beyond cap 32 to the end of the plug body, as clearly illustrated in Fig. 3. The extended ends of these grooves provide air inlet ducts 37 leading to the passages formed by grooves 36 to space 38 between the end of the plug body and the cap. The head of cap 32 is rounded or bulbous as at 39 and is formed to provide an annular knife edge 40. A central air emission opening 41 is provided in the head of the cap and is in axial alignment with a constricted emission opening 42 in the head of a sleeve-like cap 43 which fits snugly over the end of the barrel 1 and surrounds plug 2 and cap 32. The inner surface of the head of cap 43 conforms with the bulbous head of cap 32. The emission opening 42 is formed so as to provide an annular knife edge 44.

It will be apparent that some of the air passing through air passages 31 will enter ducts 37, pass through grooves 36 to space 38 and will be emitted through opening 41. The specific purpose of this construction is to provide a central body of air to prevent the formation of a cone of only partially disintegrated liquid which would otherwise normally form at the center of the emitted spray. In operation, the main body of air and the liquid mix in chamber 35 and the mixture passes over knife edge 40 and over the bulbous surface 39 and then over knife edge 44 through opening 42. The annular knife edges materially aid in the disintegration of the liquid and the result is that complete disintegration of the liquid is obtained. The central core of air, which is emitted through opening 41, prevents the inherent formation of a central cone of only partially disintegrated liquid which is an objectionable feature in devices of this nature.

The reason for having the liquid passages 34

and the air passages 36 arranged as above described with respect to the prismatic portion 28 of plug 2 will now be more clearly understood. It is desired that none of the liquid emitted from passages 34 will find its way back through the mixing chamber and into the air passages 36. This is prevented by axially aligning passages 34 with the air passages 31 so that the emitted liquid is in the path of the onrushing currents of air. Moreover, by locating the air ducts 37 in axial alignment with the apexes 30 and out of alignment with passages 34, only the desired quantity of air finds its way into the air ducts inasmuch as such air must diverge from its straight line of travel to enter the ducts. As shown clearly in Fig. 6, the passages 34 are in alignment with the upper two faces 29 while the passages 36 are in alignment with the lower two apexes 30. By means of this arrangement, the respective pairs of passages are separated and the individual passages of each pair are spaced 120° from one another. Although this arrangement is preferred, any other suitable arrangement may be used.

Continuing now with the description, it will be noted that barrel 1 is formed to provide an annular recess 45 within which resilient washers or rings 46 are seated. The barrel has a thin extending sleeve portion 47 over which cap 43 snugly fits. Washers 46, which may be of rubber or any other suitable material, are of such dimension as to seat snugly within the recess 45. These rings are of such internal diameter as to leave a small annular space 48 between them and portion 47 of the barrel. The annular edge of cap 43 is preferably tapered, as at 49, and engages the outermost ring 46. In this manner, a resilient seating for cap 43 is provided, it being understood that this cap is slidable along sleeve portion 47 of the barrel. The cap may be forced inward against the resilient action of rings 46 and this will cause the rings to contract into and fill the annular space 48 to effect a desired seal. Thus the annular space 48 serves the double purpose of allowing the resilient distortion of the rings to give the desired adjustability of cap 43 and also allows the sealing action mentioned.

Barrel 3 threadedly receives a cap 50 whose inwardly extending flange 51 engages cap 43 as at 52. The outer surface of cap 50 is knurled, as illustrated clearly in Fig. 1, so that this cap may be readily adjusted manually. By moving cap 50, sleeve 43 may be properly adjusted with respect to the bulbous head of cap 32. This will, of course, vary the area of the space 53 between the heads of caps 32 and 43. It will also vary the position of the emission orifice 42 with respect to opening 41. In this manner, the emitted spray or jet may be varied at will, since it will be obvious that the shape and consistency of the spray will depend largely upon the position of cap 43 relative to the stationary cap 32. The parts are preferably designed so that sufficient adjustment of cap 43 to completely cut off the emitted spray is possible. In other words, it will be apparent that if cap 43 is moved inwardly a sufficient distance so that the inner surface of the head thereof engages the bulbous surface of head 32, the flow of mixed air and liquid from the mixing chamber 35 will be prevented. By properly designing the parts so that such adjustability of cap 43 is possible, a wide variation in the spray, as well as complete cutting off thereof, may be effected.

When the disintegrator is assembled and in use, liquid is delivered to the knife edges in a fine film

and blown off at high speed by the air issuing from the central air emission opening 41 and the air which comes around the bulbous head 39 with the liquid. The liquid is sprayed to the knife edge 44 evenly by means of the bulbous projection 39 which is also provided with the knife edge 40 for the first stage of disintegration. The central air stream prevents a core in the jet by forcing the liquid to take a passage via the knife edge, as 10 the central air stream has a priority of exit.

Although a preferred embodiment has been disclosed herein for the purpose of illustration, various changes and modifications may, of course, be made without departing from the spirit and 15 scope of the invention. It is to be understood that the invention is not limited to the use of air as an atomizing fluid. The word "air" in certain of the appended claims is used merely for convenience and is not intended to limit the 20 invention.

I claim:

1. An atomizing device, comprising a tubular barrel having an air inlet opening, a plug within said barrel having a fluid-conducting passage 25 leading to a mixing chamber, there being air-conducting space between said barrel and said plug leading from said inlet opening to said mixing chamber, and a cap removably carried by said barrel and having a constricted emission 30 aperture, said plug terminating adjacent said emission aperture in a bulbous end having a knife edge located so that the mixed air and fluid pass over said edge, said plug having an air-conducting passage therethrough leading from said air-conducting space to a point adjacent said emission aperture.

2. An atomizing device, comprising a tubular barrel having an air inlet opening, a plug within said barrel and being substantially co-extensive 40 therewith, said plug having a longitudinal fluid-conducting passage terminating in one or more transverse passages near an end of said plug leading to an annular space between said barrel and said plug which constitutes a mixing chamber, there being air-conducting space between said barrel and said plug leading from said inlet opening to said mixing chamber, and a cap removably carried by said barrel and having an 45 emission orifice communicating radially with said mixing chamber, said plug having an air-conducting passage therethrough leading from said air-conducting space and terminating in an axial emission opening at a point adjacent said orifice, whereby the radially moving mixed air and fluid from said mixing chamber strikes the 50 jet of air from said last-mentioned passage substantially at right angles.

3. An atomizing device, comprising a tubular barrel having an air inlet opening, a plug within 60 said barrel and being substantially co-extensive therewith, said plug having a longitudinal fluid-conducting passage terminating in one or more transverse passages near an end of said plug leading to a mixing chamber, a portion of said plug being of prismatic formation with its flat faces 65 in axial alignment with said transverse passages, whereby air-conducting spaces between said barrel and said plug leading from said inlet opening to said mixing chamber are provided, and a cap removably carried by said barrel and having an emission orifice communicating with 70 said mixing chamber, said plug having air-conducting passages therethrough leading from said air-conducting spaces to a point adjacent said

orifice with one or more inlet ducts in axial alignment with the apexes of said portion.

4. An atomizing device, comprising a tubular barrel having an air inlet opening, a plug within 5 said barrel and being substantially co-extensive therewith, said plug having a longitudinal fluid-conducting passage terminating in one or more transverse passages near an end of said plug leading to a mixing chamber, a portion of said plug being of triangular prismatic formation with 10 its flat faces in axial alignment with said transverse passages, whereby air-conducting spaces between said barrel and said plug leading from said inlet opening to said mixing chamber are provided, and a cap removably carried by said 15 barrel and having an emission orifice communicating with said mixing chamber, said plug having air-conducting passages therethrough leading from said air-conducting spaces to a point adjacent said orifice with one or more inlet ducts 20 in axial alignment with the apexes of said portion.

5. An atomizing device, comprising a tubular barrel having an air inlet opening and an annular recess, a plug within said barrel having a fluid-conducting passage leading to a mixing 25 chamber, there being air-conducting space between said barrel and said plug leading from said inlet opening to said mixing chamber, packing means in said annular recess, a sleeve-like cap seated on said packing means and having 30 an emission orifice, said cap forming with said plug a passage from said mixing chamber to said orifice, and a cap adjustably carried by said barrel and engaging said sleeve-like cap, whereby 35 the emitted spray may be varied at will.

6. An atomizing device, comprising a tubular barrel having an air inlet opening and an annular recess, a plug within said barrel having a fluid-conducting passage leading to a mixing 40 chamber, there being air-conducting space between said barrel and said plug leading from said inlet opening to said mixing chamber, one or more resilient rings in said annular recess, a sleeve-like cap seated on said rings and having 45 an emission orifice, said cap forming with said plug a passage from said mixing chamber to said orifice, and a cap adjustably carried by said barrel and engaging said sleeve-like cap, whereby the emitted spray may be varied at will.

7. In an atomizing device, an annular mixing 50 chamber wherein atomizing fluid and liquid to be atomized are mixed, an emission orifice located axially with respect to said chamber, means for conveying the mixed fluid and liquid from said chamber radially to said orifice, a constricted 55 passage with an edge in the path of the mixed fluid and liquid, and means for projecting a jet of atomizing fluid axially through said orifice, whereby the atomized liquid is blown through 60 said orifice in an annular spray surrounding a central core of the atomizing fluid.

8. In an atomizing device, an annular mixing chamber wherein atomizing fluid and liquid to be atomized are mixed, an emission orifice having an annular knife edge located axially with 65 respect to said chamber, means for conveying the mixed fluid and liquid from said chamber radially to said orifice, a constricted passage with an edge in the path of the mixed fluid and liquid, and means for projecting a jet of atomizing fluid 70 axially through said orifice, whereby the atomized liquid is blown through said orifice and against the knife edge thereof in an annular spray surrounding a central core of the atomizing fluid.
